UNITED STATES PATENT OFFICE

HARRY KOMMEL, OF BROOKLYN, NEW YORK

DESIGN FOR A CARD-TABLE COVER

Application filed September 20, 1930. Serial No. 37,031. Term of patent 3½ years.

To all whom it may concern:

Be it known that I, HARRY KOMMEL, a citizen of the United States of America, residing at 789 St. Marks Avenue, borough of Brooklyn, in the county of Kings and State of New York, have invented a new, original, and ornamental Design for Card-Table Cover, of which the following is a specification, reference being had to the accompanying drawing, forming a part thereof and showing a face view of a card-table cover embodying my design.

I claim:

The ornamental design for a card table cover substantially as shown.

HARRY KOMMEL.
